US0D1046358S

(12) **United States Design Patent** (10) **Patent No.:** **US D1,046,358 S**
(45) **Date of Patent:** **** Oct. 8, 2024**

(54) **IRONING BOARD**

(71) Applicant: **Guangdong Wireking Household Supplies Co. Ltd.**, Foshan (CN)
(72) Inventor: **Jiawei Xie**, Guangdong (CN)
(73) Assignee: **GUANGDONG WIREKING HOUSEHOLD SUPPLIES CO. LTD.**, Foshan (CN)
(**) Term: **15 Years**
(21) Appl. No.: **35/515,355**
(22) Filed: **Aug. 31, 2022**

(80) **Hague Agreement Data**

Int. Filing Date: **Aug. 31, 2022**
Int. Reg. No.: **DM/223899**
Int. Reg. Date: **Aug. 31, 2022**
Int. Reg. Pub. Date: **Oct. 14, 2022**

(30) **Foreign Application Priority Data**

Jul. 13, 2022 (CN) 202230442457.3

CLAIM

The ornamental design for an ironing board, as shown and described.

DESCRIPTION

1. Ironing board

1.1: Front

1.2: Back

1.3: Bottom

1.4: Top

1.5: Left

1.6: Right

1.7: Perspective

1.8: Folded state reference

1.9: Folded state reference

The broken lines showing of the tie in Figs. 1.8-1.9 is for the purpose of illustrating environmental structure and forms no part of the claimed design.

1 Claim, 9 Drawing Sheets
